Primary Examiner—Nelson C. Holtje*Attorney, Agent, or Firm*—Browdy and Neimark[57] **CLAIM**

The ornamental design for a watch dial, as shown and described.

DESCRIPTION

The FIGURE is a top plan view of a watch dial showing my new design, the rear, now shown, being flat, plain and unornamented. The dial is of no appreciable thickness. The watchcase shown in broken-lines is environmental only and forms no part of the claimed design.

FIG 1

UNITED STATES PATENT AND TRADEMARK OFFICE
CERTIFICATE OF CORRECTION

PATENT NO. : D 361,537
DATED : August 22, 1995
INVENTOR(S) : C. FERRARA

It is certified that error appears in the above-identified patent and that said Letters Patent is hereby corrected as shown below:

Title page, column 1, item 30 (Foreign Application Priority Data), change "RM94000086" to
--RM94000086--.

Signed and Sealed this
Twelfth Day of December, 1995
